FUEL SYSTEM FOR COMBUSTION ENGINES

Homer A. Trussell, Bombay, India

Application January 22, 1940, Serial No. 314,950

6 Claims. (Cl. 261—69)

This invention relates to working fluid charge forming and induction devices for internal combustion engines, and particularly to the types known as self-feeding, plain-tube, cold-carburetion and fuel-reclaiming.

The general objective of this invention is to provide a construction whereby it is possible to obtain high efficiency of operation, fuel conservation and steady firing throughout all phases of engine operation including starting, cold operation, acceleration, power, speed and smooth transfer from any phase of operation to another, in a system relieved of several troublesome major elements some or all of which now are employed in the various conventional systems.

The above being among the objects of the present invention, the same consists of certain novel features of construction and combinations of parts to be hereinafter described with reference to the accompanying drawings, and then claimed, having the above and other objects in view.

In the accompanying drawings which show suitable embodiments of the present invention and in which like numerals refer to like parts throughout the several different views:

Fig. 1 is a side elevational view of an internal combustion engine embracing a fuel system constructed according to the principles of the invention;

Fig. 2 is a side elevational view on a larger scale of the fuel system disclosed in Fig. 1;

Fig. 3 is a fragmentary vertically sectional view taken substantially on line 3—3 of Fig. 2;

Fig. 4 is an enlarged, fragmentary horizontal sectional view taken substantially on the line 4—4 of Fig. 3, showing the third stage vaporizer; in which view the dot and dash lines indicate an air conduit contour such as is illustrated more clearly in Figs. 6, 8 and 10;

Fig. 5 is an enlarged sectional view taken centrally of the second stage vaporizer air nozzle showing how it may be adapted for air delivery from a remote point;

Fig. 6 is an enlarged vertical sectional view taken longitudinally of the preferred form of the device similar to that shown in Fig. 2, except that it is shown for the purpose of illustration as being adapted for delivery of the working fluid at a single outlet;

Fig. 7 is a longitudinal sectional view of a modified form of construction of that portion of the device shown in Fig. 6 between the lines indicated at 7, considered herein as the first stage

vaporizer, and showing an arrangement thereof which may be preferable in some cases;

Fig. 8 is a side elevational view of the structure shown in Fig. 6, taken from the opposite side thereof;

Fig. 9 is a fragmentary, approximately vertical sectional view taken on the line 9—9 of Fig. 8, and showing an arrangement of part of the control mechanism corresponding to that shown in dotted lines in Fig. 6;

Fig. 10 is a sectional view taken in the same plane as Fig. 6, showing a fragment of the device shown in Fig. 6 connected with a fragment of the internal combustion engine, also shown in similar section and including a preferred inlet port construction and also showing the compensator piston-valve in an adjustment which may be preferred in some cases;

Fig. 11 is a fragmentary sectional view taken substantially on line 11—11 of Fig. 10, and showing an arrangement of part of the control mechanism corresponding to that shown in dotted lines in Fig. 10;

Fig. 12 is a partially broken horizontal sectional view of part of a modified form of the device similar to that shown in Fig. 2 except that the manifold shape is more nearly conventional and provision is made for reclaiming fuel from either side of the venturi, and is taken substantially on line 12 of Fig. 13;

Fig. 13 is a fragmentary, partially broken vertical sectional view taken on the line 13—13 of Fig. 12.

In conventional working fluid induction systems for internal combustion engines, because of inherent characteristics thereof and/or of the carburetor, the following conditions are found to exist. Fuel is encountered in the conventional working fluid induction systems in five forms as follows: 1. As a vaporized part of the working fluid enroute to the combustion chambers. 2. As liquid particles carried in suspension with the working fluid. 3. As moisture or liquid on the walls of the induction conduits. 4. As liquid or pools on the floor or in pockets of the induction conduits. 5. As decomposition, such as carbon, soot, gum and/or impoverished gases.

Fuel exists in all five of these forms simultaneously in many engines during some phases of operation.

Conditions causing the first and second forms should be fostered to increase the proportions of fuel in these forms, care being taken to keep the particles very fine and to prevent condensa-

tion or accumulation en route to the combustion chamber inlets.

The conditions responsible for the third form are inherent to conventional fuel-air induction systems and may be made less objectionable, if not eliminated entirely, without adding heat to the working fluid, by: reducing the wall area of these induction conduits through which the fuel travels; shortening the interval of flow of fuel between the point of delivery to these conduits and the combustion chamber inlets; and/or directional flowing of unvaporized fuel to keep it off these walls. Complete vaporization by the carburetor would also help.

Conventional systems are hang-overs from the era when commercial gasoline was a first rate cleaning fluid and would vaporize rapidly at low temperatures without leaving a grease spot. Now, it cannot satisfactorily be introduced into one end of a pipe with any reasonable expectation of getting a properly formed mixture in any given proportions out of the other end of the pipe when desired, even though an excessive amount of heat be employed for vaporization thereof.

In conventional systems, an appreciable part of the fuel must be flowed over the inner walls of the induction conduits to accomplish delivery of it to the combustion chamber inlets, for the simple reasons that: the carburetors do not deliver the fuel in completely vaporized form; it is impractical to employ enough heat to prevent the fuel from existing therein in liquid form; no provision is made to compensate for the inertia and gravitational differences in the fluids in the conduits and the consequent tendency of the unvaporized fuel to lag behind the air and the vaporized fuel en route to the combustion chamber inlets; and no adequate provision is made for keeping the liquid off these walls.

The effects of this are particularly apparent upon acceleration from fractional throttle operation. During fractional throttle operation, low pressure existing in the induction system has the effect of increasing the volatility of the fuel therein and dries up or reduces the liquid on the walls of the induction conduits so that, upon an acceleration demand, it becomes necessary to pour an excess of fuel onto these walls and have it flow over the length thereof before it can be delivered to the combustion chamber inlets. Naturally, some of the fuel is carried part way or all of the way through the conduits with the gaseous portion of the working fluid without being deposited on the conduit walls and part of the liquid deposited on the walls becomes vaporized enroute, but too much of the action depends on the flowing of liquid fuel over these walls unless so much heat be applied to the induction conduits that other serious difficulties would be encountered.

This fuel for wetting of these walls in conventional systems has to be deposited quickly and quite thickly for this acceleration because it flows as such to the combustion chamber inlets over these walls and cannot do so in adequate quantity until, like a river, the liquid has been deposited in their courses. After the response to the acceleration demand has been accomplished, the fuel deposited on these walls continues on as surplus fuel to the combustion chamber inlets until the deposit on these walls reduces to normal for the then existing suction and temperature. Engine stalling frequently occurs after the throttle opening had been in-

creased for acceleration, if the throttle be closed to idling position before sufficient working fluid had been passed through these conduits to sweep them free of this surplus fuel. Further, these characteristics in conventional systems often result in "flat spots" during acceleration due to improper proportions of fuel and air in the working fluid delivery, sometimes being too rich and too lean at the same time for two or more combustion chambers; and in "bucking" during deceleration due to excess liquid fuel, which was admitted to the induction conduit for a large volume of working fluid delivery, being delivered with the reduced volume of working fluid.

As far as forming and delivering a satisfactorily vaporized working fluid charge to the combustion chambers during cold starting and warming up from frigid temperatures are concerned, conventional multiple cylinder engine fuel systems are extremely low in efficiency.

The fourth and fifth forms of fuel can and should be precluded entirely.

Most of this outline for the third form is also applicable to the fourth which often is made more prevalent by designs which tend to trap and hold liquid fuel particularly during fractional-throttle, low-temperature operation. "Loading" of the engine during acceleration often results, in designs which become burdened with fuel in this fourth form, due to the "purging" of "pools" of accumulated fuel into the combustion chambers.

A point in this connection which undoubtedly has received insufficiently serious consideration among engineers who committed manufactures to some of the conventional fuel systems is the amount and nature of liquid accumulation often occurring in the induction systems, and the amount of damage it does to the engines. Because of the extremely low efficiency of conventional systems in supplying the combustion chamber inlets with vaporized fuel during cold starting and running, liquid fuel of relatively low volatility is deposited in the induction manifold, and the natural vaporizing tendencies of induction suction and draft reduce this liquid to still lower volatility. If this residual liquid be allowed to accumulate in the manifold, it will be carried into the combustion chambers upon acceleration without being vaporized even by the draft carrying it and will result in considerable unnecessary wear and tear in the engine. Immediate reclaiming of this fuel, in whatever quantities may tend to occur with various designs which otherwise would be satisfactory, is a sure cure for the fourth form.

The fifth form results principally from excessive heating of the fuel. Even though the heat applied to the working fluid during its formation or transmission be not enough to decompose the fuel, this heating nevertheless is objectionable because it expands the working fluid and lowers volumetric efficiency, and because it results in increased latent heat in the working fluid which lowers the permissible compression ratio in the combustion chambers and reduces the ability of the working fluid to cool vital parts of the engine at the points where the heat is generated. It is commonly believed that preheating of the working fluid, prior to introduction to the combustion chambers, is necessary for fuel efficiency, regardless of whether engine performance otherwise would be desirable with a given design without preheating, but experience indicates that this

is not a fact and merely seems to be so because of sluggish action and unequal distribution tendencies in conventional systems.

This invention contemplates: Accomplishing delivery of the kind of a mixture needed at any given time from the outlet of the conduit by forming the mixture at this point at this time; having this point close to the combustion chamber inlet; employing a powerful means for vaporization of the fuel and flowing of it in an unobstructed and properly directed path to the combustion chamber inlet; throttling of the air supply, to control the working fluid volume delivery, on the influent side of the point of delivery of the vaporized fuel; introduction of the main air supply through a cool dry conduit to the point of delivery of vaporized fuel and directing of this air from this point on to the combustion chamber inlet in such a manner as to assist in keeping fuel from getting onto the conduit wall and to scrub it off, if it should get thereon; having an accurate quick-acting control for measuring and delivering the fuel and air in the correct amounts and proportions to the combustion chamber inlet to meet the requirements of the various operating conditions; keeping the fuel and the air in ingress for the formation of the working fluid, apart until immediately prior to their delivery to the combustion chamber inlet for greater facility in meeting changed operating conditions independently of preceding conditions; reclaiming of liquid fuel from the induction conduit, if it should tend to accumulate therein in spite of the foregoing, and reevaporation of this reclaimed fuel through the initial vaporizer; and recirculation of an appreciable part of the working fluid for further provision for equalization of mixture characteristics, particularly in a system feeding a plurality of combustion chamber inlets, through the initial vaporization system. Furthermore, the invention contemplates accomplishing the foregoing in a coordinated system; capable of lifting its own fuel from a supply at a lower elevation, without the aid of a fuel pump; employing the simple "plain tube" type of carburetion without any "auxiliary air valve"; requiring little or no adjustment for quick starting and flexible cold engine operation and obviating the conventional "choke" and its complicated "automatic control"; permitting the elimination of all means for preheating and, consequently, the control thereof; providing for withdrawal of liquid fuel from the induction manifold without resorting to a "manifold to ground drain"; and utilizing this liquid fuel without the aid of any supplementary device.

Referring now to the drawings and particularly to Fig. 1, an internal combustion engine 16 employed in practicing the invention comprises a cylinder block 17 having a head 18, an exhaust manifold 19 and a fuel system generally designated as 20 and comprising: The fuel supply mechanism and the first stage vaporizer 21, the second stage vaporizers 22, the third stage vaporizers 23, the main air inlet manifold 24, the second stage air inlet tubes 26, the intermediate fuel ducts 27, and the reclaimed fuel ducts 28.

In order to facilitate understanding of the construction disclosed, reference may be now had to Figure 6 which is identical to the construction shown in Figure 1 except for the fact that in Figure 6, merely a single manifold construction is shown, while the construction shown in Figure 1 employs a branch manifold construction.

As illustrated in Fig. 6, fuel enters the chamber 29 in the housing 25 through the duct 31 in the fitting 32 screwed into the housing 25, having the upright extension 33 and a valve seat 34. The valve 35 has the ball 36 on its upper end received in the socket 40 of the float 37, is guided by the extension 33 and seats at 34 when the float 37, which is pivoted on the pin 38 mounted in the housing 25, is lifted to a predetermined height by fuel in the chamber 29. This extension 33 also serves to cause incoming fuel to enter the chamber 29 through a column of liquid thereby reducing the tendency of the fuel to be vaporized upon delivery thereto, and to prevent draining thereof during protracted non-running periods. Fuel is delivered from the chamber 29 to the duct 39 by the valves 41 and/or 42, and air, or vapor, as the case may be, may be delivered from the chamber 29 to the duct 39 by the valve 43 arranged in vertical alignment above the valve 42. For convenience in this description, the fluid admitted by the valve 43 will be considered as vapor, as will also the fluid admitted to the valve 224 to be described later. A valve 41 threadably mounted in the housing 25 is provided with the external operating lever 44 having the clamp screw 46 as indicated in Fig. 6, and is adapted to seat at 41 or to vary the effective opening of the duct 49 at this point. Fuel from the chamber 29 may pass through the apertures 48 in the walls of the duct 49 past the valve 41 through the duct 49 into the duct 39, if this valve be adjusted accordingly. Fuel which may be admitted by the valve 42 to the duct 39 passes between this valve and its seat 51, and through the duct 52 to the duct 39. Vapor which may be admitted by the valve 43 to the duct 39 passes between this valve and its seat 53, and through the duct 54 to the duct 39. The valves 42 and 43 are adapted to automatically vary their respective openings or to open and close, if desired, upon a change in throttle opening.

The throttle control comprises the wheel 57 and the mechanism operated thereby. This wheel is secured to the shaft 59 which is rotatably journaled in the housing 25 and the wheel may be actuated by this shaft or by engagement of a suitable operating member with the walls of the opening 61 in the wheel extensions 63. Obviously any suitable operating rod (not shown) may be hooked in the aperture 61 to provide positive manual means for effecting rotation of the wheel 57. Overlying opposite sides of the wheel 57 are two tracks 64 and 74, each of which projects laterally beyond the wheel 57. The track 64 controls the opening of the valve 43 and is secured to the wheel 57 by the screws 66, 67, 68 and 69 threaded thereinto, and the springs 71 around these screws hold the track against the heads of the screws so the adjustment of the respective screws determines the shape of this track; that is, the radii of the track at various circumferential portions thereof. The track 74 controls the opening of the valve 42 and is secured to the wheel 57 by the screws 76, 77, 78 and 79 threaded thereinto (Fig. 8) and the springs 81 around these screws hold this track against the heads thereof so adjustment of these respective screws determines the shape of this track.

The valve 43 is adapted for control by the track 64 by the mechanism supported by the shaft 82 journaled in the housing 25. The lever 83 is secured to this shaft within the chamber 29 and the lever 84 is secured on the external part of this shaft. The lever 84 carries the pin 86 as a

journal for the roller 87 adapted to roll on the laterally projecting edge of the track 74. The lever 83 has a socket 88 to receive the rounded flange 89 on the valve 43 and is provided with a lug 90 for engagement of the spring 91 which tends to rotate the shaft 82 and hold the roller 87 against the track 64.

The valve 42 is adapted for control by the track 74 by the mechanism supported by the shaft 92 journalled in the housing 25. The lever 93 is secured on this shaft within the chamber 29 and the lever 94 is secured on the external part of this shaft. The lever 94 carries the pin 96 as a journal for the roller 97 adapted to roll on the laterally projecting edge of the track 74. The lever 93 has a socket 98 to receive the rounded flange 99 on the valve 42 and is provided with a lug 100 for engagement by the spring 101 which tends to rotate the shaft 92 and hold the roller 97 against the track 74.

The spring 111 seats at one end against the flange 89 and against the flange 99 at its other end to hold these flanges in the sockets 88 and 98 respectively, or to hold the valves 43 or 42 closed if the tracks 64 or 74 respectively be set accordingly. Hence, either of the valves 42 or 43 may be closed or have any desired degree of opening at any degree of rotation of the wheel 57 within the range of angular movement thereof depending upon the adjustment of the respective adjusting screws. Screws 66 and 76 are for fractional load operation, screws 69 and 79 are for full load operation, and screws 67, 68, 77 and 78 are for intermediate operation.

The main or primary air inlet 112 has the butterfly valve 113 supported therein by the shaft 114 journalled in the housing 25. The lever 116 is secured to an external portion of this shaft for rotation thereof and carries the adjustable stop screw 117 adapted to contact with the lug 118 on the housing 25 (Fig. 8). This lever 116 is connected for operation by the wheel arm 63 by the resilient mechanism comprising the connecting rod 119 joined to the lever 116 by the pin 121, and at its opposite end passed through the trunnion 122 pivotally mounted in the arm 63 as at 123, and is loaded by the compression spring 124 which surrounds it and has one end engaging the trunnion 122 and the other end engaging the flange 126 on the rod 119 to hold the adjusting nut 127 normally against the bottom of the socket 122 to tend to maintain predetermined angular relations of the valve 113 and wheel 57. The locknut 128 is provided to secure the adjustment of the adjusting nut 127.

Provision is made for delaying the opening movement of the valve 113 upon a movement of wheel 57 which would tend to lift the arm 116, in the form of a dashpot comprising the cylinder 131 fixed to the housing 25, the piston 132 with its by-pass holes 134 and valves 136, the piston rod 137 passing through the cover 138 secured by the screws 140, and the by-pass duct 139 with its valve 141. The connecting rod 142 has one bent end 143 engaging the head 144 of the piston rod 137, and the other bent end 146 engaging the lever 116. The valve 141 has an arm 147 for convenient adjustment thereof to vary the escapement of fluid from one side of the piston 132 to the other side thereof through the by-pass 139 to obtain the desired rate of delayed opening of the valve 113. The valve 136 provides for quick reduction in opening of the valve 113 upon a corresponding movement of the wheel 57.

Provision also is made to hasten the increase

of the pressure in the chamber 29 and to pump an additional fuel charge upon a movement of the throttle control for acceleration. The lever 148 secured to the wheel shaft 59 within the chamber 29 is connected with the piston 149 by the connecting rod 151 and the pins 152 and 153 so it is lowered and raised as the throttle control is moved toward opened and closed positions respectively. The piston 149 operates in a cylindrical bore 154 in the valve assembly 156 which includes the disc 157 tending to keep the aperture 158 in the valve closed, and the valve head 159 tending to keep the apertures 161 and 167 in the housing 25 closed. The valve 156 operates in the cylindrical bore 162 in the housing 25 and is slotted as at 163 to provide operating clearance for the lever 148. The valve 156 is urged by the spring 164 to keep its head 159 against the seat 166 in the housing 25, and is also provided with a transfer slot 167 communicating with the duct 168 formed in the housing 25. The cap 169 screws onto the threaded extension 170 of the housing 25 and serves to compress and hold the spring 164 in place and to seal the housing at this point.

Fuel is passed from the chamber 29 through the aperture 171 into the cylinder 162 below the valve 156 and on through the aperture 158 past the valve 157 into the cylinder 154 below the piston 149. When the piston 149 descends, the fuel between it and the disc 157 tends to become compressed and to cause the valve 156 to descend against the load of the spring 164 and admit air from conduit 172, positioned below the main air inlet 112, through the opening or duct 161, and to expel fuel through the transfer slot 167 into the duct 168. Fuel from the duct 168 may be discharged through the successive ducts 173 and 174, under the valve disc 176, through the duct 177, past the adjusting valve 178 and through the duct 179 to unite with the fuel charge of the first stage vaporizer. The valve 176 normally closes the ducts 174 and 177, and upon being lifted by fuel forced through duct 174, it closes the aperture 181 in the plug 182 connecting with the chamber 29, thereby permitting the fuel to be forced on through the duct 179 if the valve 178 be open. The valve 183, adjacent the lower end of the valve 156, with its adjusting arm 184 provides variable control of escapement of fuel, at this time, from the valve 156 through the aperture 186 back to the chamber 29, thereby controlling the length of time the valve 156 is off its seat 166 independently of or in combination with the delivery of this fuel through duct 179. This valve 183 may also be closed to provide an increased supply of accelerating fuel.

Air admitted from the duct 172 through the passage 161 while the valve 156 is off its seat 166, in addition to being used to hasten the increase of the pressure in chamber 29, may also be employed to increase the pressure in the compensator diaphragm chamber 272. Air from the passage 161 passing between the valve head 159 and its seat 166 passes on through the duct 187 and/or the annular chamber 188 surrounding the valve 156. The chamber 188 has the continuing ducts 189 and 191 leading to the valves 192 and 193 respectively. The valve 192 has the arm 194 (Fig. 8) for adjustment thereof and is adapted to connect either of the ducts 187 or 188 to the chamber 29 through the ducts 196 or 197 respectively and to variably restrict either of the passageways formed thereby or to shut

off both of them. The valve 193 has the arm 198 for adjustment or closing thereof and is adapted to connect the duct 191 with the diaphragm chamber 272 through the duct 211 and the recess 212 in the cover 213 of the housing 25. As indicated in Figs. 8 and 12, the chamber 29 has the cover 201, over the portion containing the float 37, secured by the screws 202 and sealed by the gasket 203.

Suction in the third stage vaporizer venturi 214 created by engine operation causes a displacement of fluid in the second stage vaporizer venturi 216 which is supplied in the form of air received externally of the chamber 29 by the second stage vaporizer nozzle 217, and in the form of fuel or fuel vapor received from the first stage vaporizer within the chamber 29 through the ducts 218, 27 and 219 and the chamber 221 intermediate and venturi 216 and nozzle 217. The main air supply comes from the inlet conduit 112 which may be formed into a rectangular cross-section as at 222 intermediate its length and deliver directly into the semi-spherical sump 223 and the venturi 214 (see dot and dash lines in Fig. 4), or through the intermediate conduits 24 shown in Figs. 2, 3, and 4.

Air passing through the venturi 214 to the engine amplifies suction in the venturi 216, and air delivered by the nozzle 217 may further amplify this suction in the chamber 221, particularly while induction suction is relatively low, so that suction at the first stage vaporizer and in the chamber 29 is adequate during all phases of engine operation for positive action by this vaporizer and for lifting fuel into the chamber 29 from a lower level, if desired, without any other fuel feeding mechanism.

The valve 224 has the arm 226 (Fig. 8) for adjustment or closing thereof and is interposed in the duct 227 between the duct 261 and the chamber 29 and provides for delivery of vapor to the first stage vaporizer charge independently of or in combination with the valve 43.

The sump 223 and the chamber 29 are connected for fluid transfer therebetween by the ducts 228, 28 and 229, and the valve 232 may be employed to control this fluid transfer. This valve is loosely pivoted on the pin 233 carried by the housing 25 and is constructed so it may seal the lower end of the duct 229. The spring 234 pivoted on the pin 236 also carried by the housing 25 is adapted to tend to keep the duct 229 closed according to the adjustment of the screw 237 threaded through the housing 25 and to have this tendency increased, if desired, through engagement of the spring 234 by the float valve socket 40 if the float level in the chamber 29 falls a predetermined amount. The screw 238 threaded in the housing 25 provides for a fixed opening for transfer of fluid between the chamber 29 and sump 223, if desired.

The valve 241 is adapted to seal the aperture 242 and provide for unloading of pressure in the chamber 29 upon a change in operating conditions which might tend to cause the suction in the conduit 222 to exceed that in the chamber 29, depending on the weight of the valve 241 or the load of the spring 243 which is variable by adjustment of the screw 244 (Fig. 8) or otherwise moving the arm 246. The screws 247 pass through the valve 241 to guide it and are threaded into the housing 25. The arm 246 is secured to the shaft 248 within the conduit 222 and carries the finger 249 which serves as a fulcrum for the spring 243 carried by the shaft 248, and

the finger 251 which may serve to hold the valve 241 closed. The lever 252 is secured to the shaft 248 externally of the housing 25, is adapted to be engaged by the screw 244 threaded through the lug 245 formed on the housing 25 and has the holes 253 and 254 for reception of suitable members for controlling the operation thereof (Fig. 8).

Provision is made for automatic control of the fuel delivered by the vaporizers during changes in pressure in the conduit 222 or the chamber 29, primarily to control changes in the fuel proportions fed during changes in the working fluid induction suction and to supply adequate fuel for acceleration, including the compensator piston-valve 256 and the operating diaphragm 257 therefor.

The valve 256 is adapted to reciprocate in the cylindrical bore 258 in the housing 25 and to close the duct 218 when in certain positions of operating, and has circumferential groove 259 formed therein which is adapted to establish communication in various degrees between the ducts 261 and 218, and also has the threaded portion 262 to engage the threaded members 263 and 264 providing for adjusting the elevation of the valve 256. The upper end of the valve 256 passes through the center of the diaphragm 257 and is clamped thereto at the desired normal elevation 20 of the valve by the members 263 and 264, and the flange 266 of the diaphragm is anchored in the counterbore 267 in the housing 25 by the ring 268, the gasket 269, and the cover 213 secured by the screws 271 (Fig. 8). The diaphragm chamber 272 may be in communication with the conduit 222 through the conduits 274 and 276 according to the adjustment of the valve 277 interposed therebetween and having the adjusting arm 278. Movement of the valve 256 may be limited by the arms 279 and the lever 281.

The arms 279 are fixed with respect to the shaft 282 journalled at one end in the housing 25 as at 283 in Fig. 12 and having its other end protruding therefrom through the bushing 284 threaded through this housing. The hub 286 is secured to the shaft 282 outside of the housing 25 and has the arm 287 with the bore 288 for reception of a suitable operating member, and also (Fig. 8) has the arm 289 with the bore 291 for reception of another suitable operating member. An adjustable stop screw 292 threaded through the extension 293 of the housing 25 and is adapted to engage the arm 289 to limit its movement in a counter-clockwise direction of movement as viewed in Fig. 8. Rotation of the shaft 282 by the arms 287 and 289 varies the elevation of the arms 279 within the housing 25 and which arms are adapted to engage the lower face of the member 263 thereby limiting the downward movement of the valve 256 and providing means for lifting this valve independently of the action of the diaphragm 257.

The lever 281 is secured to the shaft 294 within the recess 212 (part of the chamber 272 in the cover 213) and this shaft is journalled in the cover 213 and is provided with an external extension to which is secured the lever 296 (Figs. 8 and 9) having the bores 297 and 298 for reception of operating means therefor. The adjustable stop screw 299 is threaded through a lug 311 on the housing 25 and is adapted to engage the lever 296. Rotation of the shaft 294 by the lever 296 varies the elevation of the lever 281 which is adapted to engage the top of the member 264 thereby limiting the upward movement 70 75

of the valve 256 and providing means for lowering this valve independently of the action of the diaphragm 257.

Provision is made whereby either the arms 279 or the lever 281 may be operated to vary the limit of movement of or to vary the elevation of the valve 256 in conjunction with the movement of the lever 246. For this purpose, there is a connecting rod 312 (Fig. 8) with its pivoted trunnions 313 and 314 and the adjusting and lock nuts 316 and 317. The rod 312 has a hole 318 therein for reception of a suitable operating member, the flange 319 for engagement with the trunnion 314 and the threads 321 to hold the nuts 316 and 317 in the desired position for engagement with the trunnion 313, and has a sliding fit in these trunnions so either trunnion may be moved engineward, or to the right as viewed in Fig. 8, independently of the other or both may be moved simultaneously by this rod 312. The pivot 322 of the trunnion 313 engages the hole 254 in the lever 252 and the pivot 323 of the trunnion 314 may engage the hole 297 in the lever 296 as in Figs. 6, 8 and 9, or it may engage the hole 288 in the lever 287 as shown in Figs. 10 and 11.

The ball check 324 adjacent the bottom of the housing 25, with its spring 326 and retaining plug 327 may be employed to predeterminedly restrict the passage of fluid from the first stage vaporizer duct 39 and to the duct 45 thereof, to prevent reversal of flow therebetween, and to divide the "well" formed by the ducts 45, 29 and 54 into two portions so the ducts 39 and 54 may be relatively fast filling and the duct 45 relatively slow filling.

In the structure disclosed by Fig. 7, provision is made in the first stage vaporizer portion for introduction of the vapor, which is admitted thereto by the valve 43 through the duct 54a, to the duct 45a engineward of the fuel ducts 49 and 52, and for the additional ball check 328 which may be employed to prevent reversal of flow from the duct 261 through the ducts 45a and 54a. The adjusting screw 329 threaded through the wall 55 is adapted to close or vary the capacity of the aperture 331 between the ducts 54a and 45a below the fuel level in the chamber 29; the adjusting screw 332 threaded through the wall 55 is adapted to close or vary the capacity of the aperture 333 between 54a and 45a substantially at the fuel level in 29; and the adjusting screw 334 threaded through the wall 55 is adapted to close or vary the capacity of the aperture 336 between 54a and 45a above the fuel level in chamber 29.

The ball check 328 may be employed to seat at, and be adapted to seal, the mouth of the duct 45a and to lift to permit transfer of fluid from the duct 45a to the duct 261. The ball check 324 may be employed for the same purposes as in Fig. 6 except that the well in Fig. 7 is not divided thereby, and the tension of the spring 326 may also control the rate of increase of fuel in the entire well formed, in this case, by the ducts 45a and 54a.

In the structure disclosed in Fig. 10, a fragment of the structure shown in Fig. 6, with the compensator valve and its control on another adjustment, is shown attached to a fragment of an engine inlet port such as may preferably be employed in the engine 16 in combination with the preferred inclined outlet from the fuel system. The studs 337 extending through the holes 338 in the flange 339 have the nuts 340 to secure the 75

device to the cylinder block 17 so the venturi 214 delivers to the port 341 which is controlled by the valve 342. This arrangement of the port 341 and the venturi 214 provides for high volumetric delivery for given diameters thereof, high velocity of working fluid therethrough and natural draining, of fuel which might tend to accumulate therein during some phases of operation at low temperatures, away from the engine. The compensator action shown in this figure will be explained later.

In the structure disclosed in Figs. 12 and 13, provision is made for a compact main air inlet manifold 24a, delivery of fluid to horizontal engine inlet ports and in alignment therewith, and reclaiming of fuel engineward of the throat of the venturi 214a. Hence, it is evident that the delivery of working fluid is not limited to an upwardly inclined outlet from this system, that reclaiming of fuel, which might otherwise enter an engine in undesirable form during some phase of operation if cold working fluid is being delivered, is not limited to withdrawal of the fuel from the main air conduit, and that the constructions disclosed are not limited to any particular arrangement of the main air conduit, and are readily adaptable for "updraft" or "down-draft" delivery of the working fluid.

The apertures 343 and the chamber 29 may be connected for fluid transfer therebetween by the ducts 344 and 229. The control mechanism at the mouth of this latter duct, previously explained, may serve also for control of this fluid transfer. The sump 223a may extend longitudinally of the conduit 24a and be provided with the apertures 228 adjacent the venturi as shown in Figs. 6 and 10.

Fig. 5 discloses the details of the arrangement of the second stage vaporizer jet 217 which may be employed to receive air from the tube 26. The enlarged end 346 of the tube 26 is mounted on the tubular extension 347 of jet 217 which has the communicating apertures 348 for the transfer of air and the threads 349 engaged by the nut 351 to secure these units together. The plug 352 closes the outer end of the extension 347. The tube 26 may be connected with the air conduit 172 through an opening 353 in a boss 354 as shown in dotted lines in Fig. 8; the opening 353 continuing through the housing 25 to the conduit 172 as shown in dotted lines in Fig. 6.

The influent points 112, 172 and 217 are indicated for communication with the atmosphere and referred to as such herein, to avoid further complication in the drawings and description, and it is understood that the supply of air, or gas which might be used in lieu of air for admixture with the vaporized liquid fuel for formation of the working fluid, at any or all of these inlets may be at a greater or less pressure than atmospheric, due to various arrangements such as the use of air cleaners, intake silencers, pressure charging or super-charging. It is further understood that this system may have one or a plurality of working fluid delivery outlets (for examples, as shown in Figs. 6 and 1 respectively), that each of these outlets may feed one or a plurality of combustion chamber inlet ports (as, for example, through conventional working fluid induction manifolds) and that each of these ports may feed one or a plurality of combustion chambers (as, for example, through "Siamesed" inlets).

Referring particularly to Figs. 6 and 8 (inasmuch as the structure shown in Fig. 10 is a fragment of the structure shown in Fig. 6, the description of the structure shown in Fig. 10 will be omitted).

much as the operation thereof is substantially the same as the structures disclosed by Figs. 1 to 5, except that Figs. 6 and 8 have but one working fluid delivery outlet and therefore simplify the description thereof), the operation of the device will be considered from the time that the engine is at rest. As previously mentioned, fluid fed to the vaporizers from the chamber 29 above the fuel level therein, will be considered as vapor in this description.

During starting of the engine, air is displaced from the conduit 222 through the venturi 214, thereby resulting in differential pressures in the system which cause carburetion and delivery of the working fluid. The atmospheric pressure in the chamber 29 may be retarded in its tendency to balance the pressure in the conduit 222 by moving the lever 252 engineward to increase the tendency of the spring 243 and the finger 251 to hold the valve 241 so as to impede the discharge of pressure from the chamber 29 to the conduit 222. Thus, fuel will be discharged from the chamber 29 through the ducts 49 and/or 52, and vapor may be discharged therefrom through the ducts 54 and/or 227 to deliver the charge of the first stage vaporizer through the duct 261. Meanwhile, the rush of air through the venturi 214 has resulted in an additional drop in pressure at the venturi 216, and the air entering through the nozzle 217 may cause a still further drop in pressure in the second stage vaporizer chamber 221. During this withdrawal of air from the conduit 222, the diaphragm 257 will tend to lower the valve 256, because of the temporarily greater pressure in the chamber 272, to increase the fluid transfer capacity from the duct 261 to the duct 218. The ducts 27 and 219 complete the passageway from the duct 218 to the chamber 221. In this manner, extraordinary forces are available in the passageways through which the fuel feeding and vaporizing are accomplished, and the effective capacity thereof may be increased, to facilitate starting.

At this time, the lever 281 may be operated, by moving the lever 296 engineward, to prevent the valve 256 from reducing the opening of the duct 218 below a predetermined degree, which might otherwise tend to occur due to an increase in pressure in the conduit 222 (concurrently with reduced engine speed or increased opening of the valve 113); the arms 279 may be operated by moving the lever 287 engineward, to prevent the valve 256 from increasing the opening of the duct 218 beyond a predetermined degree; the valve 41 may be adjusted to control fuel delivery through the duct 49; and the valve 224 may be adjusted to control vapor delivery through the duct 227. Control of the valves 241 and 256, by operation of the levers 252 and 296 respectively, is preferred for starting and may be accomplished simultaneously by movement of the rod 312 which may be released during normal operation to permit these levers to return to their respective positions provided for by the adjustment of the stop screws 244 and 299 respectively.

Adjustment of the valves 41 or 224, by the lever 44 or the arm 226 respectively, may be made for any phase of operation, and provide for variation in the control of fuel or vapor feeding in the first stage vaporizer while permitting the adjustment of the screws 66 to 69 and 76 to 79 in the wheel 57 to be left in chosen positions. The degree of opening of the throttle valve 113 for the various phases of engine operation may be about the same as in conventional carburetion.

with the possible exceptions of minimum idling and during acceleration. Whether the valve 113 would be open during minimum idling, and if so, how much, would depend primarily upon the amount of air admitted through the second stage vaporizer nozzle 217. The opening of the valve 113 may be delayed during acceleration by the dashpot piston 132.

During normal engine operation, without any sufficiently rapid operation of the throttle control to permit delayed action of the valve 113 or lowering of the valve 156, the compensator valve 256 may stand at a given elevation to provide a predetermined opening for passage of fuel from the duct 261 through the groove 259 and out through the duct 218 during a constant pressure in the conduit 222, and it is adapted to alter its elevation to vary the opening into the duct 218 during a change in pressure in the conduit 222. The preferred arrangement of the parts of this device, and particularly the preferred proportions of the venturi 216 and the nozzle 217, may provide for "economizer" action by causing the fuel-air ratio of the working fluid to become leaner as the induction suction increases concurrently with increased engine speeds in predetermined ranges for given throttle openings.

It has been determined that changes in these ratios for this purpose may tend to cause the engine to "surge," apparently because the forces responsible for the changes in these ratios tend to be too effective during changes in induction suction, and that temporary changes, which if maintained would result in inversion of the preferred ratios, in the throttling action of the valve 256 during these changes, counteract this surging tendency of the engine. At the present stage in the development of this device, this arrangement (Fig. 6) of the compensator valve is believed to be preferable. With this arrangement, while the suction in the conduit 222 is increasing, the valve 256 may temporarily increase its opening, and while the suction in the conduit 222 is decreasing, the valve 256 may temporarily decrease its opening.

The interval required for the diaphragm 257 to return to normal position, following a change in suction in the conduit 222, may be controlled by the valve 217. The compensator chamber 272 may be connected with the fuel chamber 29, for transfer of pressures therebetween, by turning the valve 192 to establish communication between the ducts 197 and 189 which latter is in communication with the chamber 188; the remainder of the passageway to the chamber 272 being through the chamber 188, and the duct 191, the valve 193, the duct 211 and the recess 212.

This latter transfer of pressures may be employed either independently of or in combination with that controlled by the valve 217, may be varied in rate by adjusting either of the valves 192 or 193, and may be preferable in some cases because it permits the pressure which is feeding fluid to the valve 256 to influence or effect the control thereof.

Upon a quick advance of the throttle control, the valve 113 opens, according to the movement of the lower end of the spring 124 and if desired, according to the resistance encountered by the piston 132, and permits an increased amount of air to pass from the inlet 112 to the conduit 222, and the valve 156 may descend, according to the movement of the piston 149 and the resistance to flow of fuel through the duct 168, and permit air to pass from the conduit 172

through the aperture 161 to the chamber 188. Thus, air may be introduced to the chamber 29 to get an additional fuel supply on its way to the venturi 214 in anticipation of the requirement to meet the additional air coming into the conduit 222, air may be admitted to the chamber 272 to increase the opening of the valve 256 in the passageway for this additional fuel, and additional pressure may be applied to the fuel in the valve chamber 154 to provide for an accelerating "shot" of fuel for the sudden increase in the main air supply, thereby compensating for the inertia differences in the fluids and the engine requirements for richer fuel-air ratios during acceleration. Further, the valves 42 and 43 may be in changed positions corresponding to the adjustments of the tracks 74 and 64 respectively, to provide the desired working fluid characteristics for the changed throttle opening.

Air entering the chamber 188 through the aperture 161 may pass into the chamber 29 through either of the ducts 187 or 189 according to the adjustment of the valve 192. Discharge of fuel from the valve cylinder 154 through the slot 167 and the duct 168 may be through the duct 179 to combine with the fuel en route to the engine and/or through the aperture 186 to return to the fuel in the chamber 29, according to the adjustment of the valves 178 and 183. At the same time, the elevation of the valve 256 may be controlled (within the limits provided for by the arms 279 according to the position of the lever 289, and by the lever 281 according to the position of the lever 296 to provide a predetermined passageway between the ducts 261 and 218) by admitting air from the chamber 188 to the chamber 272 according to the adjustment of the valve 193 to resist the tendency of the incoming air in the conduit 222 to lift the diaphragm 257 and the valve 256.

When the fuel is discharged from the chamber 154 of the valve 156 by the urge of the spring 164, the valve head 159 may close on the seat 166 and stop the admission of air through the aperture 161. At about the same time, the valve 113 may have come to the position provided for by the actual position of the throttle control. Pressures in the chamber 29 which might tend to be excessive may be discharged through the aperture 242 controlled by the valve 241 according to the position of the lever 246 and the tension of the spring 243. The aperture 242 may be employed with or without the valve 241, or this aperture may be permanently closed.

With the valve 192 adjusted to establish communication between the ducts 189 and 197, air may pass from the conduit 172 therethrough to the chamber 29 while the valve 156 is open, the chambers 29 and 272 may be in communication through the duct 191 and communicating passages while the valve 156 is closed, and provision is made for fluid transfer between the conduit 222 and the chamber 29 through the chamber 272, thereby providing additional control of the fuel-air ratios of the working fluid.

If the throttle control be left in a given position and the engine speed does not vary rapidly enough, due to changing loads, to cause a variation from normal in the elevation of the valve 256, the fuel-air ratios of the working fluid mixture may be automatically controlled by the three stages of vaporization and the differentials in pressure according to the working fluid induction volume and suction values so that leaner ratios may be progressively formed within pre-

determinable ranges of engine speed as the engine load reduces. This economizing action may be carried out to the point that fuel delivery, through the venturi 216 stops entirely at a predetermined high induction suction during relatively high engine speeds for given throttle openings. The load of the spring 164 may be such that it would permit the valve 156 to open and admit air through the aperture 161 during predetermined high induction suction for coordination with the vaporizers in controlling the working fluid mixture characteristics or to reduce the range of suction in the chamber 29.

During operation resulting in substantially constant suction in the conduit 222, still greater suction may exist in the chamber 29 due to evacuation of fluids therefrom through the duct 261 and result in transfer of fluids thereto from the sump 223 through the ducts 228, 28 and 229. This may also occur while suction is decreasing in the conduit 222, but the flow through these ducts tends to reverse during rapid increases in suction in the conduit 222. This reversal of flow may be prevented by employing the valve 232 and in the preferred arrangement thereof, as shown, which has the screw 238 adjusted to permit the valve 232 to seal the mouth of the duct 229 and the screw 237 adjusted to cause the spring 234 to tend to hold this valve closed. The tension of this spring may be altered to control the amount the suction in the chamber 29 may exceed that in the conduit 222. The valve 232 preferably is adapted to deflect fluid entering the chamber 29 from the duct 229 to minimize the disturbance of liquid in this chamber. The screw 238 may be adjusted to hold the valve 232 open a predetermined amount, or this valve may be eliminated.

Fluid may circulate from the sump 223 through the chamber 29 and the venturi 216 in varying amounts which are controlled principally by the opening of the valves 43 or 224. Any liquid which may be present in this fluid may join the fuel in chamber 29 for feeding therewith. Fuel fed from the chamber 29 through the valves 41, 42 or 178 is replaced by fuel through the duct 31 as the fuel level in the chamber 29 recedes and permits the float 37 to relieve the pressure of the valve 35 on its seat 34 to enable the fuel in the duct 31 (under the pressure of the atmosphere or otherwise) to enter the chamber 29.

The first stage vaporizer is considered as the portion below the conduit 222 designated by the numeral 1 in Fig. 6 and, while it may feed fuel only, preferably is adapted to feed an "emulsion" of fuel and vapor from the chamber 29 through the duct 261. While the engine is at rest, fuel may stand in the ducts 45 and 54 corresponding to the fuel level in the chamber 29, thereby providing for a "well" action which may be employed to assist in starting and accelerating the engine, and in providing the fuel proportions for the other phases of engine operation. Fuel may also accumulate in the ducts 54, 39 and 45 comprising the "well" during operation resulting in a reduction, or temporary discontinuation, of fuel delivery through the duct 261, and the ball check 324 may serve to keep this accumulation relatively small at this time, compared to the capacity of the complete well, by restricting the flow of fuel between the ducts 39 and 45 so the fuel accumulates first in the ducts 39 and 54.

The ball check 324 and/or its spring 326 may be eliminated, but both preferably are used to prevent fluid from being forced back past the

valves 41 and 42 through the fuel in the chamber 29 during changes in operation which might temporarily result in proportionately excessive suction in the chamber 29, to prevent or delay the accumulation of fuel in the duct 45, and to assist in varying the fuel feeding rate to meet the requirements of the varying amounts of air passing through the venturi 214. The rate at which the duct 45 would fill by gravity, while the engine is at rest, may be controlled by the fit of the ball 324 on its seat at the mouth of the duct 39 and/or the tension of the spring 326.

It is preferred, during normal operation, to have sufficient vapor admitted by the valve 43 and passing through the ducts 54, 39 and 45 to carry fuel from the valves 41 or 42 to the duct 261 as rapidly as the fuel is delivered to the duct 39 through the ducts 49 or 52. It is also preferred to "bleed" the maximum amount of vapor through the duct 227 consistent with varying fuel feeding requirements, in order to facilitate vaporization, increase the velocity from there on through the second stage vaporizer and to increase the recirculation of fluid from the sump 223 through the chamber 29.

The first stage vaporizer portion as shown in Fig. 7 has the vapor or fuel from the duct 54a introduced to the duct 45a through "bleeds" (331, 333 and 336) engineward of the fuel feeding ducts 49 and 52 and provides for a graduated "well" action. The accumulation of fuel in both of the ducts 45a and 54a may be controlled by the ball check 324, and the additional ball check 328 may serve to prevent forcing of fuel from the well formed by these ducts back past the valve 43. This ball 328 also may be eliminated. Either of the screws 329, 332 or 334 may be adjusted to close or to provide the desired opening through the apertures 331, 333 or 336 respectively to assist in controlling the characteristics of the fuel delivered to the duct 261.

It is preferable to have the fuel from the first stage vaporizer conveyed to the second stage vaporizer through the duct 27 in a tube outside of the path of influent air, which is to be used in the formation of the working fluid, to prevent the absorption of heat by the fuel in this tube from this air during operation when a relatively high rate of vaporization in this tube would tend to result in relatively low temperatures thereof, to further reduce the difference in operation of this system during "warming up" and subsequent running of the engine, and to reduce "surging" of the engine which might result from vaporization in this tube beyond that planned or from a tendency toward "vapor lock" therein. These factors are important particularly because of the preferred small diameter of the duct 27 and the high suction therein, and the length of this duct which may be desired in some cases.

In the preferred structure, the engine valve port 341 (Fig. 10) is more nearly aligned with the axis of the engine inlet aperture than in conventional practice and the venturi 214 is adapted to feed directly to this port in a combination which has rather remarkable volumetric efficiency per diameter of engine inlet valve aperture and permits of materially increased velocity through the throat of the venturi, the most advantageous spot is chosen for delivery of fluid from the venturi 216 and all of the fuel is fed therethrough, and positive flowing of the working fluid adjacent the combustion chamber inlet results and enables the working fluid to be delivered to the combustion chamber inlets in definite

formations and materially assists in maintaining unidirectional engineward flow.

It has been observed that in some proportions and adjustments of this system, particularly wherein the reduction in fuel proportions at the higher induction suctions is carried out to the point of stopping the fuel delivery of the vaporizers while induction suction is above that within the range of engine speed under its own power (suction such as occurs in an automobile engine while coasting with the throttle closed) that the engine tends to propel itself, on light loads, up to a point where the working fluid becomes too lean and then to slow down to obtain the necessary proportion of fuel, thereby resulting in a surging tendency.

As in Fig. 10, during an increase in suction, the valve 256 lowers and reduces the opening of 218, thereby making the working fluid prematurely leaner and tending to stop the increase in engine speed and suction; then, the diaphragm 257 and the valve 256 may return to normal positions and permit the fuel proportion to be sufficiently increased without a drop in engine speed. The increase in induction suction which results in this reduction in opening of the duct 218 may also result in a temporary excess of pressure in the chamber 29, which may have less chance of feeding excess fuel out through the duct 218 because of the temporary reduction of the opening thereof, and which excess may be relieved through the aperture 242. Upon a decrease from the prevailing suction in the conduit 222, the valve 256 may temporarily increase the opening of the duct 218 while pressure is building up correspondingly in the chamber 29. Air delivered through the valve 193 during acceleration may be eliminated because the increase in the air volume, and the consequent reduction in suction, in the conduit 222 during acceleration may be depended upon to lift the diaphragm 257 and the valve 256 to increase the opening to the duct 218.

The compensator feature, as in Fig. 10 of temporarily reducing the fuel feed aperture during an increase in suction 222, and the compensator feature in Fig. 6, of temporarily reducing the fuel feed aperture during a decrease in suction in conduit 222, may be combined to correct a surging tendency while relatively high induction suction exists, and to conserve fuel while the prevailing suction is falling off in conduit 222, respectively.

This adjustment would be as shown in Fig. 10 with the valve adjusted, by means of the threaded members 263 and 264, to normally stand at a sufficiently high elevation to provide substantially a full opening of the duct 218 by the groove 259, and may preferably be used with the combined control of the levers 252 and 287 as shown in Figs. 10 and 11 to provide for a predetermined opening of the duct 218 against the suction created in the conduit 222 during starting, in which case the rod 312 may be shortened, by adjusting the nuts 316 and 317 at the trunnion 313 in the arm 252, to permit the desired action of the lever 246 without tending to move the valve 256 to close the duct 218. Air delivery through the valve 193 may also be used herewith to provide the desired opening of the duct 218 during acceleration.

It is understood that the valve 256 may be adjusted for any desired normal elevation with the lever 252 connected for combined operation with either of the levers 287 or 296.

The conduit 222 is adapted to deliver air to the manifold 24 or 24a through an opening having a length exceeding its height, the length of this

opening being substantially parallel to that of this manifold; and it is understood that the length of this opening (the mouth of the conduit 222) may be extended to equal the length of the manifold 24 or 24a and that the height of this opening may be reduced.

An advantage of this feature is that the incoming air may be spread out to assist in accomplishing equalized distribution of this air and fuel in the manifold 24 or 24a; particularly in engines wherein the intervals between inspirations through the manifold 24 (or 24a) are unequal (as for instance, in a conventional two cylinder V type motorcycle engine) or in engines wherein the intervals between inspirations through a plurality of intake ports fed by one of the venturis 214 (or 214a) are unequal (as for instance, in a conventional four cylinder, in-line, four-cycle engine with two intake port passageways, each feeding two siamesed ports) or in engines where in a combination of the above unequal intervals occur in some parts of the induction system, if not all of it (as for instance, in a conventional six cylinder engine).

The adaption of this system to multiple cylinder engines, wherein the working fluid is to be formed at a plurality of manifold outlets, may be accomplished in numerous ways and, for sake of avoiding further complication in this application, the arrangement of this system for formation of the working fluid at a plurality of outlets therefrom is disclosed only in the dual outlet arrangements as shown in Figs. 1, 2 and 12. In Figs. 1 and 2, the conduit 222 is bifurcated into the two manifold branches 24, the duct 218 is bifurcated into the two ducts 27, and the duct 229 is bifurcated into the two ducts 28. In Fig. 12, substantially the same structural characteristics occur; the manifold branches having the designations 24a, and both of the ducts 344 also connecting with the duct 229. In these figures, the unidirectional flowing tendency of the working fluid components engineward through the dual venturis 214 or 214a, mitigate the tendency toward "pumping" action between combustion chamber inlet ports, which exists in conventional induction manifolds.

While for the purpose of illustration, only a plurality of forms of the invention have been disclosed herein in detail, it will be apparent to those skilled in the art not to be so limited but that various other forms and applications of the invention may be made within the scope of the invention as set forth by the appended claims.

What is claimed is:

1. In a charge forming device having a primary conduit with a throttle valve therein for delivering a supply of working fluid to an internal combustion engine and having a closed fuel supply chamber, valve means for controlling the supply of fuel from said closed fuel supply chamber to said conduit for forming a working fluid in said conduit, a diaphragm for controlling said valve means, means for exposing one side of said diaphragm to the pressure existing in said conduit between said throttle valve and said engine, and means for exposing the opposite side of said diaphragm to the pressure existing in said closed fuel chamber.

2. In a charge forming device having a primary conduit with a throttle valve therein for delivering a supply of working fluid to an internal combustion engine and having a closed fuel

supply chamber, valve means for controlling the supply of fuel from said closed fuel chamber to said conduit, a diaphragm serving to control the position of said valve means, one side of said diaphragm being exposed to the interior of said conduit between said throttle valve and the point of delivery of the working fluid to said engine, and means establishing communication between said closed fuel chamber and the opposite side of said diaphragm.

5 3. In a charge forming device having a primary conduit with a throttle valve therein for delivering a supply of working fluid to an internal combustion engine and having a closed fuel supply chamber, valve means for controlling the supply of fuel from said closed fuel chamber to said conduit, a diaphragm serving to control the position of said valve means, one side of said diaphragm being exposed to the interior of said

15 conduit between said throttle valve and the point of delivery of the working fluid to said engine, and means establishing communication between said closed fuel chamber and the opposite side of said diaphragm, and means for adjustably controlling said last mentioned means.

20 4. In a charge forming device having a primary conduit with a throttle valve therein and a closed fuel chamber, means for delivering fuel from said closed fuel chamber to said conduit for the formation of a working fluid therein, valve means for controlling the delivery of said fuel, a diaphragm for controlling said valve means, one side of said diaphragm being exposed to the interior of said conduit, a conduit establishing communication between the interior of said first mentioned conduit and the opposite side of said diaphragm, and a conduit establishing communication between the interior of said closed fuel chamber and the opposite side of said diaphragm.

25 5. In a charge forming device having a primary conduit with a throttle valve therein and a closed fuel chamber, means for delivering fuel from said closed fuel chamber to said conduit for the formation of a working fluid therein, valve means for controlling the delivery of said fuel, a diaphragm for controlling said valve means, one side of said diaphragm being exposed to the interior of said conduit, a conduit establishing communication between the interior of said first mentioned conduit and the opposite side of said diaphragm, and a conduit establishing communication between the interior of said closed fuel chamber and the opposite side of said diaphragm.

30 6. In a charge forming device having a primary conduit with a throttle valve therein and a closed fuel chamber, means for delivering fuel from said closed fuel chamber to said conduit for the formation of a working fluid therein, valve means for controlling the delivery of said fuel, a diaphragm for controlling said valve means, one side of said diaphragm being exposed to the interior of said conduit, a conduit establishing communication between the interior of said first mentioned conduit and the opposite side of said diaphragm, and a conduit establishing communication between the interior of said closed fuel chamber and the opposite side of said diaphragm, and adjustable valve means in each of said last mentioned conduits for controlling communication therethrough.

35 7. In a charge forming device having a primary conduit with a throttle valve therein for delivering a supply of working fluid to an internal combustion engine and having a closed fuel supply chamber, valve means for controlling the supply of fuel from said closed fuel chamber to said conduit, a diaphragm serving to control the position of said valve means, one side of said diaphragm being exposed to the interior of said conduit between said throttle valve and the point of delivery of the working fluid to said engine, and means establishing communication between said closed fuel chamber and the opposite side of said diaphragm, and means for adjustably controlling said last mentioned means.

HOMER A. TRUSSELL.
